Primary Examiner—A. Hugo Word*Assistant Examiner*—Ruth McInroy*Attorney, Agent, or Firm*—Palmatier, Sjoquist & Helget[57] **CLAIM**

The ornamental design for a combined head and body protector for sparring, as shown and described.

DESCRIPTION

FIG. 1 is a front elevational view of a combined head and body protector for sparring showing my new design;

FIG. 2 is a rear elevational view thereof;

FIG. 3 is a left side elevational view thereof;

FIG. 4 is a right side elevational view thereof; and,

FIG. 5 is a top plan view thereof.

The person shown in broken lines in FIGS. 1-5 is for illustrative purposes only and forms no part of the claimed design. The cross-hatch shading shown in all views is understood to repeat throughout the indicated area.
